UNITED STATES PATENT OFFICE.

NATHANIEL A. HADDEN, OF SANDUSKY, OHIO.

FRUIT-BASKET COVER.

SPECIFICATION forming part of Letters Patent No. 352,313, dated November 9, 1886.

Application filed September 23, 1886. Serial No. 214,357. (No model.)

To all whom it may concern:

Be it known that I, NATHANIEL A. HADDEN, of Sandusky, in the county of Erie and State of Ohio, have invented new and useful 5 Improvements in Fruit-Basket Covers; and I do hereby declare that the following is a full, clear, and exact description thereof, reference being had to the accompanying drawings, which form a part of this specification.

10 This invention relates to a new and useful improvement in covers for fruit-baskets; and the invention consists in the peculiar construction of the cover and its combination with the basket, all as hereinafter described.

15 In the drawings which accompany this specification, Figure 1 is a detached perspective view of my improved cover. Fig. 2 is a side view of a basket provided with my cover. Fig. 3 is a plan of the cover with the basket 20 shown in dotted outlines, and Fig. 4 is a cross-section of Fig. 2.

The essential parts of my cover comprise two light strips of wood, A A, the corresponding ends of which are secured together by thin 25 cross-slats B B. The strips A A are a little longer than the length of the basket, and are drawn together at the ends, so as to make the distance between these ends less than the width of the basket, while in the middle the 30 strips are just far enough apart to permit the handle to pass through tightly when the cover is placed on top of the basket, as shown. By this means the shape of the cover can be made to conform near enough to the shape of the 35 basket, while the following advantages are gained: The cover is supported by the strips resting on the edge of the basket at several points, without any possibility of their slipping over the edge, and thereby injuring the 40 fruit underneath, and as the handle is firmly embraced between the two strips A no accidental displacement can take place, and therefore the cover need not be secured, unless it was done for other reasons. By giving the 45 strips A A a suitable height the baskets may be used to their full capacity, and in shipping they may be piled on top of each other with-

out injury to the fruit, as the cross-slats protect the open ends.

To have the cover answer all purposes, I 50 preferably secure in the intervening space between the cross-slats B a few more additional slats, C, to the strips A, and place them close enough together to prevent the withdrawal of fruit through the openings between; or, if desired, I secure a strip of netting to the cross-bars B, to cover such intervening space.

If slats are used, I preferably place one slat on each side of the handle. By this means the cover is held still more firmly in position.

As a new article of manufacture, my cover presents the advantages that it can be manufactured very cheap, and although it may be made very light it has all the elements of strength, the strips A being placed on edge.

What I claim as my invention is—

1. A cover for fruit-baskets, consisting of the strips A, drawn toward each other at the ends, and of the cross-slats B, secured thereto, all so arranged that the cover is supported on 70 the top of the basket by the strips A, resting on the sides and ends of the basket and embracing the handle, substantially as described.

2. A cover for fruit-baskets, consisting of the strips A, drawn toward each other at the 75 ends, of the slats B, nailed across said ends, and of intervening cross-slats, C, all so arranged that the cover is supported on the top of the basket by the strips A, resting on the sides and ends of the basket and embracing 80 the handle, all substantially as set forth.

3. As a new article of manufacture, a cover for fruit-baskets, consisting of the strips A, placed on edge and drawn toward each other at their ends, of the cross-slats B, nailed across 85 the corresponding ends of the strips, and of the intervening cross-slats, C, one of which is placed on each side of the handle, all arranged substantially as described.

NATHANIEL A. HADDEN.
